UNITED STATES PATENT OFFICE

JAMES M. BONNER, JR., OF LOS ANGELES, CALIFORNIA

HOUSING FOR FLUSH PIPES

Application filed May 28, 1929. Serial No. 366,598.

This invention relates to a housing for covering a flush-pipe connecting a flush-tank with a flush-bowl. The general object of the invention is to provide a housing of simple construction which can be readily put in place between the tank and the flush-bowl and which will finish out the closet with earthenware without necessitating the use of any mortar or cement for making the connection between the bowl and the tank.

A further object of the invention is to provide a device of this kind with simple means for supporting it on the flush pipe and for centering the same.

The device comprises a housing preferably formed of porcelain or similar material, and one of the objects of my invention is to give this housing an improved form to facilitate its maintaining itself in place between the flush tank and the bowl, and also to construct the housing and a retaining spring within it in a correlated manner so that the spring will retain itself within the housing without necessitating the use of a separate fastener to hold it in place.

Further objects of the invention will appear hereinafter.

The invention consists in the novel parts and combination of parts to be described hereinafter, all of which contribute to produce an efficient housing for flush pipes.

A preferred embodiment of the invention is described in the following specification, while the broad scope of the invention is pointed out in the appended claims.

In the drawings:

Fig. 1 is a side elevation of the flush-tank and flush-bowl and illustrating the housing embodying my invention set in place.

Fig. 2 is a front elevation of the parts shown in Fig. 1.

Fig. 3 is a plan of the housing removed from the bowl and with its wall partially broken away to further illustrate the construction of the housing.

Fig. 4 is a vertical section through the housing taken on the line 4-4 of Fig. 3, its relation to the flush-pipe being illustrated by the use of dotted lines showing the position of the flush-pipe.

In practicing the invention I produce a housing 1 which is preferably formed of earthenware having a finish to correspond with the finish of the flush-bowl 2. The housing is of shell form, that is to say, it is 55 hollow and formed with a relatively thin shell-like wall 3.

The upper portion of the housing is enlarged laterally into a relatively large head 4, the upper end of which is formed into a 60 seat face 5 to seat against the under side of the bottom 6 of the flush-tank 7. The lower portion of the housing is formed with an outwardly offset neck 8 of reduced dimensions laterally and the lower end of this neck is 65 formed with a seat face 9 which may rest upon the upper face 10 of the bowl (see Fig. 1). In order to facilitate the application of the housing to the flush-pipe 11 that connects the tank and the bowl, the inner side of 70 the housing is formed with a relatively large opening 12. The presence of this opening permits the housing to be shoved into position so that its upper end is received in the angle formed between the face 13 of the wall 75 and the bottom of the tank.

The interior of the housing is provided with means for centering the housing on the flush pipe and this means is preferably in the form of a spring 14 formed of wire and 80 constructed so as to engage the spuds 15 of the flush-pipe above the coupling nut 11^a (see Fig. 4). This spring may have any desired shape but the spring and housing are of correlated form so that the spring is 85 capable of cooperating with socket means within the shell to retain itself in the shell. This avoids the necessity for providing a separate fastener to retain the spring. For this purpose the spring is preferably formed 90 at its ends with extensions or spurs 16 that are received in openings 17 formed in the rear wall of the housing.

The spring is formed with two coils or bows 18 between which the material of the 95 wire is bent to form a deep throat 19 opening toward the wall 13, the inner end of the throat being closed by bight or bend 20 in the wire. When the housing is shoved back into place the bight 20 operates as a socket 100

to receive the flush-pipe thereby operating to center the flush-pipe and to hold it in position.

It is understood that the embodiment of the invention described herein is only one of the many embodiments this invention may take, and I do not wish to be limited in the practice of the invention, nor in the claims, to the particular embodiment set forth.

What I claim:

- 10 1. A housing for covering a flush-pipe between a flush-tank and a flush-bowl consisting of a body of shell form having an opening on its rear side to enable the same to be placed around the flush pipe by a lateral movement and having a substantially flat seat face on its upper side to seat against the under side of the bottom of the flush tank, and a resilient metal frame having means for engaging around the pipe to center the housing upon the same, said housing having socket means cooperating with the resilient frame to retain the same in the housing.
- 15 2. A housing for covering a flush-pipe between a flush-tank and a flush bowl consisting of a shell form body of earthenware having an opening on its rear side to enable the same to be placed around the flush pipe by a lateral movement, the upper portion of said body being enlarged laterally and having a substantially flat seat face to lie adjacent to the underside of the bottom of the tank, a spring located in the upper portion of the housing, said housing and spring having a correlated form enabling the housing to retain the spring within the housing, said spring having a bight formed therein forming a socket to receive the flush pipe and center the housing thereupon.
- 20 3. A housing for covering a flush-pipe between a flush-tank and a flush-bowl consisting of a shell form body of earthenware having an opening on its rear side to enable the same to be placed around the flush pipe by a lateral movement, the upper portion of said body being enlarged laterally and having a substantially flat seat face to lie adjacent to the underside of the bottom of the tank, a spring located in the said laterally enlarged upper portion of the housing, said housing having socket means for engaging the spring to retain the same within the housing, said spring having a bight formed therein forming a socket to receive the flush pipe and center the housing thereupon, said housing having a reduced extension at its lower portion with a seat face at its lower end adapted to seat on the upper face of the bowl.
- 25 4. A housing for covering a flush pipe between a flush-tank and a flush-bowl consisting of a body of earthenware having an opening on its rear side to enable it to be placed around the flush pipe by a lateral movement, the lower portion of said body being relatively narrow and the upper portion of said

body being relatively wide and having a seat face at its upper end to lie adjacent to the under-side of the bottom of the tank, and means within the housing for centering the same on the flush pipe.

5. A housing for covering a flush pipe between a flush-tank and a flush-bowl consisting of a body of earthenware having an opening on its rear side to enable it to be placed around the flush pipe by a lateral movement, the upper portion of said body being enlarged laterally and having a seat face at its upper end to lie adjacent to the under-side of the bottom of the tank, and means within the housing for centering the same on the flush tank, said housing having a relatively narrow laterally off-set lower portion with a seat face at its lower end to seat against the upper face of the bowl.

Signed at Walnut Park, Calif., this 20th day of May, 1929.
